METHOD AND APPARATUS FOR MAKING BOOK MATCHES

Application filed October 27, 1926. Serial No. 144,551.

This invention relates to a method and apparatus for making book matches, that is, strips of matches formed of paper which are bound together in book form.

5 Among the objects of the invention are to provide a method and an apparatus whereby a strip of paper or cardboard is subjected to a plurality of automatic operations in immediate and automatic succession to each other so as to produce strips of matches to be subsequently bound into book form, the plain strip of cardboard entering the apparatus at one point and the complete strip of matches leaving the apparatus at another point without 10 the intermediate intervention of any manual operation.

Another object is to provide such a method which consists in successively and automatically slitting a sheet of cardboard to form 20 match sticks or stems, spreading the sticks or stems, cutting a strip of sticks or stems from the sheet, dipping the ends of the sticks into paraffin, subsequently dipping the sticks into the usual composition to form the heads, and 25 drying the heads.

A further object is to provide novel and improved construction and combination of apparatus for automatically performing said steps of the method, whereby a sheet of cardboard 30 may be slit, cut up into strips, dipped into paraffin and into the head-forming composition and dried, so that match strips may be continuously produced with a minimum of labor and handling and consequently at a low 35 cost.

Other objects are to provide a novel and improved construction and combination of cutting devices and match strip conveyors and strip holding devices; to provide such apparatus which shall be simple and inexpensive in construction and operation, and to obtain other results and advantages as may be brought out by the following description.

Referring to the accompanying drawings, 40 in which corresponding and like parts are designated throughout the several views by the same reference characters,

Figure 1 is a side elevation of apparatus embodying the invention for making strips of 45 matches;

Figure 2 is a top plan view thereof, portions being omitted for clearness in illustration;

Figure 3 is an enlarged vertical longitudinal sectional view, taken on the line 3—3 of Figure 2;

Figure 4 is a top plan view of the conveyor for receiving the match strips from the slitting and cutting mechanism as viewed from the line 4—4 of Figure 3;

Figure 5 is a transverse vertical sectional view, taken on the line 5—5 of Figure 3;

Figure 6 is an enlarged fragmentary sectional side elevation of a portion of the conveyor shown in Figure 3 and a portion of the second conveyor;

Figure 7 is a transverse vertical sectional view, taken on the line 7—7 of Figure 6;

Figure 8 is a detached perspective view of one of the match strip gripping clips;

Figure 9 is a view similar to Figure 6 showing another portion of the second conveyor and its relation to the reservoir for the igniting composition, and

Figure 10 is a vertical sectional view, taken on the line 10—10 of Figure 2 showing the Geneva gear mechanism for feeding the cardboard with a step by step motion.

Specifically describing the illustrated embodiment of the invention, the reference character A designates the sheet feeding, slitting and cutting mechanism, B designates the conveyor for receiving the match strips from the mechanism A, C the second conveyor for removing the match strips from the conveyor B and dipping the same into the inflammable liquid, for example melted paraffin contained in a reservoir D, and into the semi-fluid igniting composition such as is commonly used for the heads of matches and contained in a reservoir E. The paper or cardboard from which the match strips are to be formed is taken from a roll F and fed to the mechanism A with a step by step motion, said roll being mounted in bearings 1 on the main frame of the machine and the sheet of cardboard or paper passing upwardly over a guide plate 2 and downwardly in a substantially vertical plane into the mechanism A.

The sheet of paper or cardboard is prefer- 100

ably of a width to form a plurality of groups of match sticks arranged side by side and each composed of ten sticks or stems.

The mechanism A includes a frame 3 at the upper portion of which and at approximately the end of the guide plate 2 is arranged a die 4 having two parallel vertical rows of openings 5 with which cooperate two corresponding parallel rows of punches 6 which are carried by the brackets 7 mounted on the ram 8 of a punch press of known construction mounted to move horizontally in guides 9. The ram 8 is reciprocated by a pitman 10 from a drive shaft 11 in known manner, said drive shaft being driven by a belt and pulley 12 from any suitable source of power and being controlled by a clutch 13 of suitable construction. With this construction, it will be obvious that upon each reciprocation of the ram 8, the punches 6 will enter the openings 5 of the die 4 and punch a corresponding number of holes 14 in the sheet of paper or cardboard, as shown in Figures 3 and 5 of the drawings. Mounted on a shaft 15 extending transversely of the frame 3 are a pair of toothed wheels 16 the teeth of which are adapted to enter the openings 14 of the corresponding row, as shown in Figure 5 of the drawings, and said shaft is rotated with a step by step motion coordinately with the reciprocation of the ram 8 so that the sheet of cardboard or paper is moved forward one step upon each movement of the ram 8 to withdraw the punches 6. Any suitable mechanism may be utilized for so driving the shaft 15, but preferably a Geneva gearing is utilized comprising the usual plate 17 having a plurality of radial notches 18 with which cooperates with a pin 19 carried by a wheel 20 mounted on a countershaft 21 and driven by a chain and sprocket gearing 22 from the drive shaft 11. It will be obvious that the shaft 15 will be rotated through an angle of 90 degrees upon each complete revolution of the wheel 20, and the ratio of the gearing is such as to produce movement of the sheet of paper or cardboard the necessary distance; and this distance corresponds to the length of the match strip which it is desired to produce.

The ram 8 carries a cutting die 25 which cooperates with a similar cutting die 26 mounted upon the frame 3, said dies being constructed to slit the sheet of cardboard or paper to form four groups 27 of match sticks each comprising ten sticks 28, and rectangular openings 29 separating the adjacent groups 27. The dies 25 and 26 cooperate to slit the sheet of cardboard simultaneously with the punching operation of the punches 6. After this slitting operation, that is upon the outward movement of the ram 8, the Geneva gearing is operated to move the cardboard through another step which in Figure 3 of the drawings moves the slitted portion of the cardboard downwardly one step so the

end of the strip is close to the shearing or cutting blades to be later referred to.

The ram 8 also has projecting from its face below the die 25 a plurality of pins or fingers 30, and a plurality of alternately spaced pins or fingers 31 are arranged on the frame 3 of the machine in approximately the same horizontal plane as the pins 30. The spacing of these pins corresponds to that of the match sticks 28, so that one of the pins 30 is substantially opposite one match stick while one of the pins 31 is substantially opposite the next adjacent match stick. As the ram 8 is moved on its next inward stroke to slit the cardboard in a new place, the pins 30 move between the adjacent pins 31 so that portions of the length of the match sticks 27 are forced into staggered relation which causes their ends to spread, as shown in dotted lines Figure 3, of the drawings when the ends are next severed. Thus, one series of groups of match sticks are staggered substantially simultaneously with the slitting of the next succeeding series of groups of match sticks.

Below the pins 30, the ram 8 has mounted thereon a cutting blade 32 which cooperates with a similar blade 33 on the frame 3, said blades being so located as to be substantially opposite the lower ends of the sticks 27 as above described. On the next movement of the Geneva gearing the cardboard strip is fed forward as already explained, until the strip is in the position of the full lines Fig. 3, then substantially simultaneously with the staggering of the sticks in the intermediate position of the match strips by the pins 30 and 31, or slightly subsequently thereto, the knife blades 32 and 33 sever the cardboard along the ends of the match sticks of the intermediate group so that the said ends are separated from each other, at a point spaced from the other ends of the match sticks so that a match strip 34 consisting of four groups of match sticks each composed of ten sticks connected at one end, is formed. It will be noted that the last-mentioned cutting operation also transforms the openings 29 into notches 35 which extend inwardly from the edge of the strip corresponding to the free ends of the match sticks to points adjacent the opposite edge of the strip, which edge constitutes the butt edge of the strip and is used for binding a plurality of the strips into book form.

Directly beneath the blades 32 and 33 and in spaced relation thereto are mounted on the frame 3 a pair of spaced and parallel horizontal rods 40 which correspond in position to the two outer notches 35 of the match strip, and during the last step of movement of the sheet of cardboard the match strip 34 moves downwardly and the notches 35 slip over the corresponding rods 40. When the blades 32 and 33 sever the match strip from the sheet of cardboard, the strip falls by gravity so that

the inner ends of the notches 35 frictionally bear upon the rods 40. Two endless conveyor chains 41 connected by spaced transverse rods 42 are mounted on sprockets 43 so that the upper reaches of the chains 41 move substantially parallel to the rods 40 and each two adjacent rods 42 receive between them one of the match strips 34, as clearly shown in Figure 3 of the drawings. These conveyor chains 41 may be driven in any suitable manner from the drive shaft 11, the speed of movement of the chains being such that one match strip 34 drops between each two adjacent cross-roads 42. As the conveyor chains move, the cross-roads 42 push the match strips 34 longitudinally of the rods 40. It will be observed that the match strips are substantially vertically edgewise disposed on the rods 40 with the butt edges projecting upwardly from the conveyor and freely exposed, the strips being held in this vertical edgewise position by gravity.

The match strips 34 are automatically removed from the rods 40 by the conveyor C for the dipping operations in the inflammable liquid and the igniting composition; and as illustrated, the conveyor C comprises two spaced and parallel metal endless belts 50 mounted to move over the respective pulleys 51 and 52 in a substantially horizontal plane, one end of the belts 50 partially overlying the rods 40 with a portion of the lower reaches of said belts 50 substantially parallel to said rods, as shown in Figures 1 and 6, and the lower reaches of said belts 50 passing over idler rollers 53 and 54, the latter of which are adjustable to serve as belt tighteners. Mounted on the belts 50 extending transversely therebetween are a plurality of equidistantly spaced friction gripping devices 55 which as shown include sheet metal plates 56 having one edge disposed at substantially right angles as at 57 and riveted as at 58 to the belts 50, said plates 56 having integrally formed therewith spring fingers 59 adapted to receive between themselves and the respective plates the butt ends of the match strips. The gripping devices 55 are so spaced on the belts 50 and so related to the rods 40, and the belts 50 are moved at such speed, that as the said gripping devices are moved by the belts 50 downwardly over the rollers 51, the spring fingers 59 of each gripping device are forced downwardly over the butt edge of one match strip 34 so as to grip the butt end thereof, as shown in Figure 6 of the drawings. The belts 50 are driven in the same direction as are the chains 41, and after the match strips have been gripped by the gripping devices 55 they are removed from the rods 40 and carried by the belts 50 and gripping devices 55 with the free ends of the match sticks in depending position. The belts 50 may be driven in any suitable manner, but preferably by means of chain and sprocket gearing 60 from the shaft

11, and the chains 41 may be driven by chain and sprocket gearing 62 from the conveyor C, the ratio of said gearing being such as to produce the proper relative speeds of movement of the two conveyors B and C.

The match strips 34 are conveyed by the lower reaches of the belts 50 to the reservoir D containing the inflammable liquid, such as melted paraffin, which is preferably disposed directly beneath the adjustable idler roller 54; and the level of the melted paraffin relative to the belts 50 as they pass over the rollers 54 is such that the ends of the match sticks are dipped into the paraffin a predetermined distance which may be adjusted to some extent by the rollers 54 and also by adjustable supports 63 for the reservoir D. The paraffin may be maintained at proper liquid consistency in any suitable manner as by a steam heating coil 64, and preferably the level of the paraffin maintained constant by any suitable means such as a float controlled inlet valve.

From the reservoir D the match strips are carried by the belts 50 into another room as through an opening 65 in a partition 66, and there dipped into the igniting composition contained in the reservoir E. This igniting composition is in a semi-liquid state, and to ensure substantially equal amounts of the composition being applied to each of the match sticks, I may use a belt 67 formed of suitable material such as rubber and movable over rollers 68 and 69 so that the upper reach 70 is substantially horizontal and normally parallel to the corresponding portions of the lower reaches of the belts 50 and above the level of the composition in the reservoir, the lower reach of the belt passing through the composition, as shown in Figure 9 of the drawings. The ends of the match sticks are dipped into the composition several times so as to ensure a secure adhesion of equal amounts of the composition to the sticks, and for this purpose I may mount upon the top of the reservoir a pair of bars 71 provided intermediate their lengths with upstanding projections 72 over which must pass projections 73 on the undersides of the belts 50. These projections 73 may be the heads of the rivets which secure the gripping device 55 to the belts. The reaches of the belts 50 are of course taut but somewhat flexible so that as the projections 73 pass over the projections 72 the reaches of the belts 50 are successively raised and lowered with snap actions which cause corresponding movements of the ends of the match sticks out of and into the composition carried by the upper reach of the rubber belt 70, as clearly shown in Figure 9 of the drawings. As indicated, the match sticks of each of the strips 34 are dipped into the composition three times, since there are at least three match strips at a time over the reservoir E and are all lifted away from the

belt 70 as each set of projections 73, associated with each match strip, engages the projections 72 on bars 71, and after having been dipped are conveyed away from the reservoir E with certain portions of the composition adhering to the ends of the sticks. The extent of the dipping movement of the match sticks into the composition may of course be determined by the movement of the reaches of the belts 50 toward and from the belt 70, it being obvious that the match sticks cannot be dipped into the composition a greater distance than the thickness of the composition upon the belt 70.

15 The distance of travel of the match strips after they leave the reservoir E may be as desired, the atmosphere through which they are moved being a dry atmosphere for drying the igniting composition picked up 20 by the match sticks from the reservoir E.

The match strips 34 may be removed from the conveyor C at any suitable point, but as illustrated the strips are carried by the belts 50 back to their starting point and there removed by arms 74 which are arranged eccentric to the rollers 50 and enter recesses 75 in the plates 56 of the corresponding devices under the butt edges of the match strips, as clearly shown in Figure 6 of the drawings, so that the match strips are pushed from the respective gripping devices by the arms 74 and fall by gravity. A conveyor belt 76 may be arranged beneath the arms 74 to receive the match strips as they fall and 35 convey them to any suitable point for subsequent operations.

From the foregoing, it will be observed that complete match strips may be formed from a strip of cardboard in a continuous process and without any manual intervention between the first operation upon the cardboard and the removal of the complete strips from the apparatus. The apparatus is simple and comparatively inexpensive in 40 construction and operation so that match strips may be economically produced.

While I have shown and described the apparatus as embodied in certain details of construction, and the method as consisting in 45 a certain sequence of certain steps, it will be understood that this is primarily for the purpose of illustrating the principles of the invention and that many modifications and changes may be made in the details of construction of the apparatus and in the carrying out of the method without departing from the spirit or scope of the invention. Therefore, I do not desire to be understood as limiting myself except as required by the 50 following claims when construed in the light of the prior art.

Having thus described the invention, what I claim is:

1. The method of making strips of matches 55 from paper or cardboard consisting in feed-

ing a sheet of paper or cardboard from a roll with a step-by-step motion, slitting a portion of said sheet of paper or cardboard upon each step of movement to form match sticks, spreading said sticks into staggered relation upon the next step of movement of said sheet and initially cutting off a portion of said sheet at the outer ends of said sticks to separate the same in spaced relation, cutting said sheet in spaced relation to the inner ends of 70 said sticks to form a strip of sticks upon the next step of movement of said sheet, depositing said strip upon a conveyor in predetermined edgewise position, automatically transferring said strips to another conveyor 80 in said edgewise relation, conveying said strip with the free ends of said sticks depending and dipping said ends of the sticks sequentially into an inflammable substance and into an igniting composition to form heads, 85 drying said heads, and removing said strip from said conveyor.

2. The method of making strips of matches from paper or cardboard consisting in unrolling predetermined amounts of cardboard or 90 paper from a roll with a step-by-step motion, presenting a portion of said cardboard to a cutter for slitting said cardboard to form match sticks upon one step of movement, presenting said portion to fingers for spreading 95 said sticks into staggered relation upon the next sequential step of movement, presenting said portion of cardboard to a cutter upon the next step of movement for cutting said cardboard on a line spaced from the open end 100 of said sticks to form a match strip and to separate the match sticks of the next following match strip, depositing said strip in edgewise position upon a conveyor, automatically transferring said match strip to another conveyor in said edgewise position, and moving said strip with the free ends of said match sticks in depending position sequentially relatively to a quantity of melted paraffin and a 105 quantity of head forming composition, so that the free ends of said sticks are dipped into said paraffin and said composition.

3. The method of making strips of matches from paper or cardboard consisting in unrolling predetermined amounts of cardboard 115 or paper from a roll with a step-by-step motion, presenting a portion of said cardboard to a cutter for slitting said cardboard to form match sticks upon one step of movement, presenting said portion to fingers for spreading 120 said sticks into staggered relation upon the next sequential step of movement, presenting said portion of cardboard to a cutter upon the next step of movement for cutting said cardboard on a line spaced from the open 125 end of said sticks to form a match strip and to separate the match sticks of the next following match strip, depositing said strip in edgewise position upon a conveyor, automatically transferring said match strip to an 130

- other conveyor in said edgewise position, moving said strip with the free ends of said match sticks in depending position sequentially relatively to a quantity of melted paraffin and a quantity of head forming composition, so that the free ends of said sticks are dipped into said paraffin and said composition, and subsequently moving said strip by said conveyor through a drying atmosphere.
4. The method of handling a plurality of strips of match sticks having notches extending from the edge of the strip corresponding to the free ends of said match sticks toward and adjacent the opposite or butt edge, consisting in suspending said strips by gravity from said notches upon a conveyor in predetermined spaced relation so that the strips are in edgewise position with said butt edges projecting upwardly from said conveyor and exposed, automatically transferring said strips to another conveyor by gripping said butt edges of said strips, and conveying said strips so held by said butt edges.
5. Apparatus for making strips of matches from paper or cardboard, comprising means for feeding with a step-by-step motion a sheet of paper or cardboard in substantially a vertical plane, means for slitting said sheet upon each step of movement to form a plurality of match sticks, means for spreading said sticks into staggered relation upon the next step of movement of said sheet, means for cutting said sheet along one end of said sticks substantially simultaneously with said spreading operation to separate said ends, and to form from a preceding operation a strip of match sticks, all of said slitting, spreading and cutting means being movable in horizontal planes transverse to the movement of said sheet and said strip being discharged by gravity from the last-mentioned cutting means in vertical edgewise position, and means for receiving said strip as it is so discharged and moving it horizontally in said position.
